UNITED STATES PATENT OFFICE

CHARLES V. MCINTIRE, OF EAST ORANGE, NEW JERSEY, ASSIGNOR TO CONSOLIDATION COAL PRODUCTS COMPANY, OF WILMINGTON, DELAWARE, A CORPORATION OF DELAWARE

DISTILLATION APPARATUS

Application filed October 19, 1922. Serial No. 595,490.

The general object of my present invention is to provide improved distillation apparatus especially adapted for use in the so-called low temperature carbonization of lignite or analogous non-coking carbonaceous material.

- 5 The various features of novelty which characterize my invention are pointed out with particularity in the claims annexed to and forming a part of this specification.
- 10 For a better understanding of my invention, however, and its advantages and specific objects attained with its use, reference should be had to the accompanying drawings and descriptive matter in which I have illustrated and described a preferred embodiment of my invention.

Of the drawings:

Fig. 1 is a sectional elevation of which the portion to the left of the line X, is taken on 20 the line 1—1 of Fig. 2, while the portion to the right of the line X is taken on the line 1A—1A of Fig. 2;

Fig. 2 is a sectional elevation, the left hand portion of which is taken on the broken line 25 2—2, and the right hand portion of which is taken on the line 2A—2A of Fig. 1;

Fig. 3 is a section taken on the broken line 3—3 of Fig. 1; and

Fig. 4 is a partial sectional plan taken on 30 the broken line 4—4 of Fig. 2.

In the embodiment of my invention illustrated in the drawings, the distillation apparatus comprises a series of vertical retorts A, and a series of vertical retorts A'. The 35 retorts A are arranged side by side, and each adjacent pair of retorts A is separated by a heating wall formed with a plurality of vertical heating flues B. The retorts A', which may be identical with the retorts A, 40 are arranged side by side, and each adjacent pair of retorts A' are separated by a heating wall formed with vertical heating flues B. The retorts A are separated from the retorts A' by a wall formed with vertical gas distillation off-take flues C located one between each adjacent pair of retorts A and A'.

The walls of the body portions of the retorts A and A' are formed of fire brick, but each side wall of the upper portion of each 50 of the retorts A and A', is advantageously

formed of metal and in the preferred construction illustrated, comprises a series of cast iron boxes or flues D of rectangular cross section stacked one on top of another. The boxes D are formed with ports to pass 55 the spent heating gases entering the lowermost box D from the tops of the adjacent heating flues B through the masonry ports B', back and forth in a zig zag passage to a corresponding outlet pipe D' connecting the 60 uppermost box D to a flue or conduit E through which products of combustion pass to a suitable stack (not shown,) or other draft creating device. Advantageously also the lower portion of each retort side wall is 65 formed, as shown, of cast iron metal boxes or flues F stacked one above the other, and formed with ports to provide a zig zag passage through which air is supplied to the flues B to support combustion. The air 70 passing through each set of boxes F enters the lowermost box from the atmosphere through a damper controlled inlet port F', and passes from the uppermost box F through a masonry port G' into a corresponding masonry channel G, which extends 75 beneath the adjacent heating wall and is provided with ports B² opening into the heating flues B above it. Fuel gas is supplied to the bottom of each flue B through 80 a port B³ in the bottom wall of each flue and a corresponding gas supply pipe L', the upper end of which extends into the port B³, and the lower end of which is connected through a suitable regulating valve to the fuel gas 85 supply piping L.

The lignite, or other material to be distilled, is introduced in granular form into the upper end of each retort A and A' through a suitably shaped conduit H preferably formed of metal, and advantageously connected to a hopper or conveyor system (not shown), in such manner as to keep the conduits H continuously filled with the material to be distilled. At the lower end 90 of each of the retorts A and A' I provide a rotating valve J regulating the discharge of the solid residue of the distillation operation into a conduit I which is advantageously connected at its lower end as shown, to the 95 100

casing of a screw conveyor for carrying away the solid residue. As shown the various discharge valves J under the retorts A, are all driven from a shaft J¹⁰, and the discharge valves J under the retorts A' are all driven by a shaft J¹⁵. By suitably varying the rotative speeds of the shaft J¹⁰ and J¹⁵, the rate at which material to be distilled is passed through the various retorts from the hoppers 10 H may be regulated as desired.

To facilitate the withdrawal of gases and vapor from the various retorts A and A', I provide in the body portion of each retort, a superimposed series of metallic parts O each in the form of an inverted trough, and provide a superimposed series of similarly shaped metallic parts P in the upper portion of each retort. The parts O are supported at their ends in seats formed for the purpose 15 in the end walls of the corresponding retort. As shown the seat for the inner end of each part O is formed by the wall of a masonry port C' through which distillation gases rising beneath the part O pass into the 20 gas off-take channel C. Advantageously the discharge ends of the port C' have their under walls downwardly inclined to facilitate the escape of liquid carried by or formed by the condensation of the gases passing through 25 the ports. The distillation products passing downwardly through the channels C are discharged through branch pipes R' into a suitable take-off conduit R. The masonry seats for the outer ends of the trough shaped parts 30 O, are advantageously formed by the walls of inspection and clean-out openings O¹⁰ in the outer masonry walls of the retort structure, these openings being normally closed by suitable doors T. The inner ends of the 35 parts P are advantageously seated as shown, in recesses formed in the masonry, and their outer ends are seated in ports formed in corresponding metallic conduits Q of which there are one for each retort. Each conduit 40 Q is connected at its upper end to the stack flue E. Advantageously a damper Q is provided to regulate the suction put on each conduit Q.

Advantageously the heating flues B and 45 the gas off-take flues C are formed with extensions B⁵ and C⁵ respectively, through the top wall of the retort structure, which are normally closed at their upper ends, but which may be opened to permit inspection 50 and cleaning operation when necessary. The retort structure as a whole may advantageously be mounted on supporting columns Y as shown.

The general method of operation of the 60 apparatus disclosed will be apparent to those skilled in the art. The lignite or other material treated is supplied to the tops of the retorts as required to keep the retorts full, or practically full, of material at all times. The 65 rate at which material is passed through the

retorts is directly controlled by the operation of the discharge valves J. As the material passes progressively down through the retorts it is dried, and partially heated in its passage through the portion of the retort in which the parts P are located. The water vapor and other vapors and gases driven out of the material in these portions of the retorts are of little or no value, and are discharged through the ports O and conduits Q to the stack. As the material moves downward past the parts O in the body portion of the retort, it heats up gradually to a maximum temperature which is attained at or near the level of the lower ends of the heating flues B. With the arrangement disclosed, the gases and vapors distilled out of the material in the body portion of the retort can escape freely and quickly from the highly heated portions of the retort. This minimizes the detrimental "cracking" of the hydrocarbons in the gases and vapors resulting from their exposure to relatively high temperatures. In a way also, the parts O serve as agitating devices to stir the material flowing past them and thus expedite the distillation process. To augment this agitation effect, and to provide an ample gas collecting space beneath each trough part O, the latter are made of considerable width, and the bodies of the retorts A and A' are made wider than the entrance and exit portions of the retorts.

As the solid residue of the distillation process passes downward between the side walls formed by the air cooled boxes F, it is cooled to a temperature suitable for discharge past the valves J, and into the conveyor system K. The heat absorbed by the boxes F serves to preheat the air passing through those boxes to the flues B and thus adds to the heat economy of the apparatus. The heat absorbed by the incoming material from the gases passing through the metallic boxes D minimizes the chimney heat loss and thereby augments the heat efficiency of the apparatus. The fact that the side walls of the retort chambers at their upper and lower ends are metallic facilitates the heat absorption by material distilled at the upper ends of the retorts and the cooling of the solid residue of the distillation process at the lower ends of the retorts.

The general construction and arrangement of the distillation apparatus permits of a masonry retort construction in which suitable expansion joints may be provided while avoiding objectionable leakage through the brick walls of the retorts proper. The method of supplying gas and air for its combustion to the heating flues, and for withdrawing the products of combustion from the flues permit of a very accurate regulation of the heating effect of each of the heating flues and also facilitates the maintenance of pressures

in the retort chambers and in the heating flues which minimize leakage in either direction through the brick work joints or cracks which may develop in operation in the walls of the retort chambers. The described construction 5 facilitates inspection, cleaning and repair operations as they become necessary from time to time. In case the material being distilled clogs between the walls of the retort chambers 10 and the parts O, the clogged material may be loosened and dislodged by the use of a suitable bent cleaner rod inserted through the adjacent cleanout opening O¹⁰. In case of fracture of one of the parts O, it is a comparatively simple matter to remove enough of the 15 outer wall of the retort chamber to permit the removal of the broken parts and the inserting of a new part in place.

While the apparatus disclosed is suitable 20 for various uses, its comparative simplicity in construction and operation, and its inherently low initial cost of construction, especially adapts the apparatus for use in treating lignite at a maximum temperature of about 25 900°F., to recover volatile by-products therefrom and to produce a solid residue of relatively high B. t. u. value and well adapted for briquetting.

While in accordance with the provisions of 30 the statutes I have illustrated and described the best forms of my invention now known to me, it will be apparent to those skilled in the art that changes may be made in the form of the apparatus disclosed without departing 35 from the spirit of my invention as set forth in the appended claims, and that certain features of my invention may sometimes be used to advantage without a corresponding use of other features.

Having now described my invention, what 40 I claim as new and desire to secure by Letters Patent, is:

1. Distillation apparatus comprising a compact masonry body formed with a multiplicity of spaced apart vertical retorts of 45 relatively small horizontal cross-section and a plurality of separate vertical channels formed in the body parallel to said retorts and distributed in the portions thereof between the retorts, said body being formed with 50 ports connecting said retorts to some of said channels whereby the latter are adapted to serve as offtake flues for distillation gases evolved in the retorts, and means associated 55 with the other channels whereby the latter serve as heating flues for the retorts.

2. Continuous distillation apparatus comprising a masonry body portion with a plurality of vertical retorts and heating flues at the 60 sides of the retorts, chambered metallic structures forming the side walls of upper and lower end portions of the retorts and with the chamber space in said structures serving as flues, and provisions for passing 65 the air supporting combustion into the heat-

ing flues through the metallic structure flues at the lower ends of the retorts, and provisions for drawing the products of combustion from said heating flues through the metallic structure flues at the tops of the retorts. 70

3. In continuous distillation apparatus comprising a masonry body formed with vertical masonry retort chambers through which the material to be distilled may flow downward, the improvement which consists 75 in gas discharging means consisting of horizontally elongated parts of inverted trough shape which extend across each retort at different levels and are mounted at their ends in the masonry retort walls, the latter being formed with ports through which the gases rising under said parts may escape from the retorts.

4. Continuous distillation apparatus comprising a masonry structure with vertical 85 retort chambers, and with distillation off-take flues at the inner sides of the retort chambers and with a plurality of ports at different levels connecting each retort chamber to an off-take flue, and with clean-out 90 openings in the wall of each retort chamber opposite to that in which the said ports are formed, said openings being in horizontal alignment with said ports, metallic parts of inverted trough shape located in said retort 95 chambers and having their ends seated in the walls thereof with the trough cavity of each in alignment with a cleanout opening and a port.

5. Distillation apparatus comprising a 100 masonry body formed with two rows of vertically disposed retorts and with flued heating walls between the retorts in each row, and with distillation gas off-take flues in the walls between the two rows of retorts. 105 and with ports connecting each retort with a corresponding off-take flue.

6. In a retort structure, the improvement which consists in a retort wall portion formed of horizontally disposed cast iron boxes 110 stacked one on top of another and formed with registering ports connecting the interiors of said boxes to provide a zig zag flue passage through said boxes.

Signed at New York City, in the county of 115 New York and State of New York, this 18th day of October A. D. 1922.

CHARLES V. McINTIRE.
